ELECTRON DISCHARGE APPARATUS OF THE
VELOCITY MODULATION TYPE

John Heaver Fremlin and Christopher Henry Foulkes, London, England, assignors, by mesne assignments, to International Standard Electric Corporation, New York, N. Y., a corporation of Delaware

Application February 19, 1943, Serial No. 476,465
In Great Britain February 19, 1942

23 Claims. (Cl. 250—27.5)

1

The present invention relates to electron discharge apparatus of the velocity modulation type and has for its object to provide an improved construction of ultra high frequency oscillator or other tube adapted to work, for example, at a wave length around three centimeters and comprising an improved arrangement by which power may be taken therefrom.

According to the invention an electron discharge device of the velocity modulation type comprises a cavity resonator system having a plurality of resonant cavities and a conducting path coupling at least two of said resonant cavities and an antenna mounted within the envelope of said device and in electrical contact with said path so as to be excited by said system.

The electron discharge device, as will be apparent to those skilled in the art may be of the simple cavity resonator reflected beam type or of the type having two or more cavity resonators with a beam suffering reflection or not. The antenna may also comprise a single rod antenna or a dipole antenna or any other shape which produces the type of electromagnetic wave it is desired to set up and transmit.

The electron discharge apparatus according to the invention is particularly adapted for use with wave-guides or with other cavity resonators to which the output from the electron discharge device may be fed, for example to a mixing cavity device as the superheterodyning frequency for receiving ultra high frequency waves to give an intermediate frequency.

In the case of a rod antenna where the antenna is excited by direct electrical contact with the resonator system, the connection is made in the vicinity of a voltage anti-nodal point of the system, and in the case of a dipole, one of the connections of the dipole is made at or in the vicinity of a voltage anti-nodal point of the system and the other connection to the dipole is made at or in the vicinity of a voltage anti-nodal point in opposite phase to the first point. These points of connection are adjustable so as to match or adjust the output impedance of the system to the antenna impedance.

The invention will be better understood from the following description taken in conjunction with the accompanying drawings which show by way of example one embodiment of the invention.

In the drawings, Fig. 1 is a plan view of the interior of the apparatus, Figs. 2 and 3 are side views looking in the directions of the arrows A and B respectively in Fig. 1, but of the complete

apparatus and with the evacuated envelope shown in section, and Fig. 4 is a perspective view of a cross-section taken along the line 4—4 in Fig. 2.

The apparatus shown in the drawings comprises an electron discharge device of the velocity modulation type having a cavity resonator system 1 comprising two cavity resonators 2 and 3, shown as double chambers 2, 2a and 3, 3a, connected by slots or gaps as shown at 4. The chambers are of cylindrical formation and are built up to any desired length from a plurality of like metal stampings as described in the specifications of our copending application Serial No. 457,789, filed September 9, 1942, for Ultra-high-frequency oscillation generators. The electron beam producing arrangement comprises a cathode 5, control electrode 6, anode 7 and collector electrode 8. The electrons therefore travel from right to left of the drawing in Fig. 1 and pass gaps in the cylindrical walls of the resonator system, so as to be modulated in velocity in passing the first chambers 3, 3a and to give up energy in passing the second chambers 2, 2a, as is now well known. A suitable voltage is applied to the anode 10 and according to the mode of operation whether the anode potential is such that the anode reflects or collects the electrons, the electrons will be collected on the resonant chamber structure, or by the electrodes 7 and 8. The electrode 8 is primarily of experimental value as an oscillator detector. The anode 7 is provided with a small aperture which allows some of the electrons to pass through to the electrode 8 and the presence of oscillations is shown by the current in an outside circuit connected to 8. The electrode 8 plays no essential part in the operation of the tube and in its absence its share of current is taken by the anode 7.

The lower end of the chamber system is closed 40 by means of a dished plate or cap 10 and the upper end terminates in a thick plate 9, apertured as the laminations. The rod antenna 12 is secured in electrical contact to the top of the plate 9, at an anti-nodal point as already explained, and may be supported for instance in an eyelet which is welded to the top of plate 9 and also to the end of the rod antenna.

The stack of plates 1 and end member 9 sandwich between them a mica plate 13 of annular formation as shown in Figure 2, and a lamination of smaller dimensions than the other laminations of stack 1 is inserted in the aperture in mica plate 13 so as to maintain the metallic and electrical continuity of the stack and top plate 9. A further mica plate 14 is provided at the bot-

tom of the stack 1 and between the mica plates 13 and 14 are mounted in position with respect to the chambers, the electron gun electrodes 5, 6, 7 and 8.

On the upper end of the chamber structure is mounted a plate 15 having an upper part which is of such diameter as to contact with a metallic portion of the envelope referred to later, and a lower portion of the same outer dimensions as chamber structure 1. The plate 15 has a central aperture 16 as shown in Figs. 2 and 3 to allow the antenna 12 to pass freely therethrough. The upper surface of the plate 15 may be dished or of other form to function as a reflector for the electromagnetic waves emitted by the antenna.

The plates of the chamber structure 1 together with the plates 13, 14 and 15 are held together by bolts 18 (Fig. 1) formed on the plate 15 or otherwise provided and by nuts 19 screwed on the ends of the bolts. The whole structure is mounted on the base of a U-shaped member 17, through which pass two of the bolts 18. This member 17 is then secured to two supporting pillars secured in the press of the envelope. A lead-in wire is connected to one of these supporting pillars and to a pin in the base, so that a potential may be applied to the resonator structure. The electrodes 5, 6, 7 and 8 have also lead-in wires connected to respective pins in the base in a manner usual in electron discharge devices. The cathode heater pins are 32 and 31 and pin 31 has no connection.

The envelope of the apparatus comprises a main body portion 20, provided with the press and secured in the base in well known manner. Into the other end of this body portion is sealed a tubular metallic piece 21. This part 21 has a portion of reduced diameter as shown and the envelope is closed by a glass cap 23 which may be of lead glass for ease of sealing, sealed to the upper edge of the part 21. When assembled the plate 15 makes direct electrical contact with the interior surface of the part 21 and a suitably apertured plate 22 is fixed in electrical contact with the outer surface of the part 21. The disc 22 is soldered to the part 21 after the valve is pumped and the space between 21 and 22 may be filled with a low melting point solder. The part 21 and the member 22 may comprise a single apertured disc sealed into the wall of the tube and concentric therewith, the plate 15 then making electrical contact with the part of the disc projecting into the interior of the envelope.

In use, the end of a wave guide or of a cavity resonator or other similar device to which it is desired to feed the ultra high frequency electromagnetic waves, is placed over the end of the envelope to make electrical contact with the plate 22 which may be provided with apertures or other suitable means for securing the wave guide or resonator thereto.

While a rod antenna has been shown in the drawings, it will be understood as already pointed out hereinbefore that other forms of antenna may be used depending upon the type of wave it is desired to transmit. Furthermore other constructions of resonant chamber systems and other velocity modulation devices may be used in carrying out the invention. Furthermore, other suitable supporting means may be provided for the antenna, but any mica parts used must be arranged as in the above described example so as to prevent any direct mica connection between the oscillating field round the antenna and the outside of the laminated stack 1 as leakage of

high frequency power of a serious nature may occur.

While the embodiment given by way of example has been described as an oscillator, it will be understood that the electron discharge apparatus according to the invention may take on other functions, for example as an amplifier.

What is claimed is:

1. An electron discharge device of the velocity modulation type comprising a plurality of cavity resonators, conducting means forming a common external wall for at least two of said cavity resonators and providing an electrical conducting path externally of the cavities of said resonators and coupling said two resonators together, and an antenna external to said cavity resonators and mounted directly on said conducting means at a point in said external conducting path so as to be excited by said system.
2. An electron discharge tube of the velocity modulation type comprising an evacuated envelope, a cavity resonator system in the form of a block built up of a series of apertured plates forming a plurality of cavity resonators, conducting means forming a common external wall for at least two of said cavity resonators and providing an electrical conducting path coupling said two resonators together, means for producing an electron beam through said system, means supporting said block and said conducting means on the press of the tube, and an antenna external to said resonator and mounted on and in contact with said conducting means so as to be excited by the electric waves on said conducting means, said antenna being enclosed within said evacuated envelope.
3. An electron discharge device of the velocity modulation type comprising a cavity resonator system having a plurality of tubular cavity resonators, conducting means forming a common external wall for at least two of said cavity resonators and providing an electrical conducting path coupling said two resonators together, a plate mounted on the end of said system and having an aperture therein, an antenna external to said resonators passing through said aperture and mounted directly on said conducting means so as to be excited by the electric waves occurring on said plate, and an apertured member carried by the envelope of said device and electrically connected with said plate.

4. An electron discharge device of the velocity modulation type comprising a cylindrical evacuated envelope, a cavity resonator system having a plurality of cavity resonators of cylindrical form mounted within said envelope with their axes parallel to the axis of said envelope, conducting means forming a common external wall for at least two of said cavity resonators and providing an electrical conducting path superficial to said system coupling said two resonators together, and an antenna external to said cavity resonators and mounted within the envelope of said device and directly on said conducting means so as to be excited by the electrical waves occurring on said conducting means.

5. An electron discharge device of the velocity modulation type comprising an evacuated envelope and, mounted within said envelope, cavity resonators of uniform transverse sections along the respective linear longitudinal axes, said axes being parallel to each other, each having a longitudinal aperture in the wall thereof parallel to the respective longitudinal aperture 75 in the wall thereof parallel to the respective

longitudinal axes of said resonators, means for producing a beam of electrons of substantially rectangular transverse section and for directing said beam past said apertures in turn, a conducting plate arranged transversely with respect to said resonators forming an external end wall for said resonators and providing an electrical conducting path within said envelope coupling said resonators, and an antenna external to said resonators and mounted directly on said plate so as to be excited by the electric waves occurring on said plate.

6. An electron discharge tube according to claim 2 further comprising a metallic member sealed into the wall of the evacuated envelope making electrical contact with the block, whereby the tube may be conveniently mounted in a transmission system and the block may be earthed.

7. An electron discharge device according to claim 2, said antenna comprising a conducting rod with its longitudinal axis parallel with the axis of the said envelope.

8. An electron discharge device according to claim 2 further comprising a metallic member sealed into the wall of the evacuated envelope, and means making electrical contact between said member and said resonator system, whereby the device may be conveniently coupled to radiate into a load device and the resonator system may be earthed.

9. An electron discharge device according to claim 5 further comprising a metallic member sealed into the wall of the evacuated envelope and means making electrical contact between said member and the walls of said cavity resonators whereby the device may be conveniently coupled to radiate into a load device and said walls may be earthed.

10. An electron discharge device according to claim 5, said beam being directed with the greater dimension of its transverse section parallel to said longitudinal axes.

11. An electron discharge device of the velocity modulation type comprising a resonating cavity system having a plurality of cavity resonators built up from a stack of like apertured conducting plates and coupled together by means of the conducting path provided by an end plate, means for producing a beam of electrons and for directing said beam with its greater transverse dimension parallel to the depth of said stack, slots in said conducting plates for coupling the resonators of said system to the electron beam, and an antenna external to said stack and mounted directly on said end plate so as to be excited by the electrical waves occurring on said path.

12. An electron discharge device according to claim 11 further comprising a metallic annular member sealed into the wall of the evacuated envelope, means making electrical contact between said member and said stack of like apertured conducting plates, said means comprising a conducting plate having an aperture through which said antenna passes, whereby the device may be conveniently coupled to radiate into a load device and said stack may be earthed.

13. An electron discharge device of the velocity modulation type, comprising a resonating cavity system having cavities of uniform cross sections along their respective linear longitudinal axes and gaps connecting said cavities with a beam gap, said system comprising a stack of thin metal stampings having apertures therein

shaped to correspond to the desired cross sections of the resonant cavities and slots corresponding to the gaps and the end plate closing one end of the resonant cavities formed by the apertures in said stampings, a source of electrons, means for forming the electrons into a beam, means for directing said beam along said beam gap, and an antenna external to said stack mounted on the end plate and in contact therewith so as to be excited by the ultra high frequency waves occurring on said plate.

14. An electron discharge device according to claim 13 further comprising an annular metallic member sealed into the wall of the evacuated envelope, means making electrical contact between said member and said stack of metal stampings, whereby the device may be conveniently coupled to radiate into a load device and said stack may be earthed.

15. An electron discharge device of the velocity modulation type, comprising a plurality of like conducting plates, each having a plurality of apertures in alignment and slots connecting said apertures to the edges of said plates, said plates being so stacked one upon another that the corresponding apertures of said plates are in alignment forming cavity resonators and the corresponding slots are in alignment and a conducting end plate closing one end of at least two of said cavity resonators, a source of a beam of electrons adjacent to said stacked plates, means mounted adjacent to beam path for directing said beam past the slots of a plate in succession with the longer dimension of the transverse section of the beam parallel to the depth of the stack, and an antenna external to said cavity resonators and mounted on and in contact with the end plate of the stack so formed so as to be excited by electrical waves occurring on said end plate.

16. An electron discharge device according to claim 15 comprising further conducting plates preferably of high heat resistance having like apertures to those in the first mentioned plates but no slots, said further plates being interleaved between said first mentioned plates in the stack with their apertures in alignment with the apertures in said first mentioned plates, said further plates forming a grid on the beam path.

17. An electron discharge device according to claim 15 further comprising an annular metallic member sealed into the wall of the evacuated envelope, means making electrical contact between the stack of conducting plates and said member, whereby the device may be conveniently coupled to radiate into a load device and said stack may be earthed.

18. An electron discharge device of the velocity modulation type comprising a plurality of like conducting plates each having a plurality of apertures in alignment and slots connecting said apertures to the edges of said plates, half the number of said plates being stacked one upon another so that corresponding apertures of said plates are in alignment forming a cavity resonator and the corresponding slots are in alignment, the other half of the plurality of plates being formed into a like stack forming a cavity resonator, means retaining the two stacks in fixed relative positions with corresponding slots directly opposite each other and with a space to form a beam gap between said stacks, a conducting end plate closing one end of each said resonator, a source of a beam of electrons adjacent to said stacked plates, means arranged ad-

7
jacent to the beam path for directing said beam along said beam gap with its greater transverse dimension parallel to the depth of the stack, and an antenna external to said cavity resonators and mounted in contact with the said end plate so as to be excited by the electric waves occurring on said end plate.

19. An electron discharge device according to claim 18 comprising further conducting plates of high heat resistance having like apertures to those in the first mentioned conducting plates but no slots and located relatively to each other as are the apertures in the two assembled stacks, and slots connecting the apertures of a pair in said further conducting plates corresponding to a pair of apertures on either side of said beam gap and immediately opposite each other, said further plates being interleaved between the conducting plates of the said two stacks with their apertures in alignment with corresponding apertures in said stacks and forming a grid across the beam gap.

20. An electron discharge device according to claim 18 further comprising an annular metallic member sealed into the wall of the evacuated envelope, means making electrical contact between the two stacks of conducting plates and said member, whereby the device may be conveniently coupled to radiate into a load device and said stacks may be earthed.

21. An electron discharge device of the velocity modulation type, comprising two stacks of like apertured conducting plates positioned to leave a beam gap therebetween for the passage of an electron beam, the apertures in said plates forming cavities of uniform cross section along the depths of the stacks and longitudinal slots connecting the said cavities with the beam gap, further conducting plates preferably of high heat resistance interleaved with the plates of said two stacks to form a grid across said beam gap and having apertures corresponding to said cavities and slots connecting apertures in opposite sides of said beam gap, a source of electrons, means for forming the electrons into a beam, means for directing said beam along said beam gap with the greater dimension of the transverse section of the beam parallel to the depth of the

stack, and an antenna mounted on and in contact with the end plate of at least one stack so as to be excited by the electric waves occurring on said end plate.

5 22. An ultra high frequency electron discharge device according to claim 21 further comprising thicker plates at the top and bottom of the stack of plates and like apertured to said further conducting plates to define the greater depth of the beam gap, and a further thicker plate at the antenna end having an aperture, said antenna passing through said aperture so as to be insulated from said further thicker plate.

10 23. An electron discharge device according to claim 21 further comprising an annular metallic member sealed into the wall of the evacuated envelope an internal conducting plate mounted on the antenna end of said stack, making electrical contact between said stack and said annular member, an aperture in said internal conducting plate through which the said antenna passes, and a conducting plate external to the evacuated envelope and having an aperture therein, the periphery of said aperture making electrical contact with said annular metallic member, whereby the device may be conveniently coupled to radiate into a load device and said stacks may be earthed.
